his Attorney.

UNITED STATES PATENT OFFICE.

RIDGEWAY REGARS, OF BURLINGTON, NEW JERSEY, ASSIGNOR TO UNITED STATES CAST IRON PIPE & FOUNDRY COMPANY, OF BURLINGTON, NEW JERSEY, A CORPORATION OF NEW JERSEY.

RING-HEATING FURNACE.

Application filed January 25, 1924. Serial No. 688,427.

To all whom it may concern:

Be it known that I, RIDGEWAY REGARS, a citizen of the United States of America, and resident of Burlington, in the county of Burlington and State of New Jersey, have invented a certain new and useful Improvement in Ring-Heating Furnaces, of which the following is a true and exact description, reference being had to the accompanying drawings, which form a part thereof.

My invention relates to a special form of furnace especially designed for heating steel rings or annular bands such as are commonly used in connection with pipes, the rings being shrunk on the end of the pipe to reinforce it and to serve other useful purposes.

The object of my invention is to provide a simple and effective furnace for heating these rings prior to their application to the pipe ends, and the nature of my improvements will be best understood as described in connection with the drawings in which—

Figure 1 is a sectional elevation of my furnace taken on the line 1—1 of Fig. 2, showing a ring in position within the furnace, and in dotted lines a ring located immediately outside of the furnace.

Figure 2 is a sectional plan on the line 2—2 of Fig. 1, and

Figure 3 is a perspective view of a device used for supporting the ring in the furnace.

A indicates the furnace which is made up of vertical walls A¹ and A², distant from each other slightly more than the width of the band which it is intended to heat in the furnace. The bottom, back and top of the furnace are made up of a flat portion A³, constituting the bottom, a curved portion A⁴, constituting the back of the furnace, and a straight portion A⁵, forming the top of the furnace. These portions may be formed integral with one of the side plates A, for instance, as shown in the drawings. The front A⁶ of the furnace is open for the full height of the furnace and is provided with a door B, by which it can be partially closed,

leaving openings B¹ at the bottom and B² at the top. C is a track which may conveniently consist of a U beam, as shown, extending into and outside of the bottom of the furnace and having at its inner end located within the furnace a device indicated at D, upon which the ring to be heated rests and which so elevates the ring that the heat-in gases can pass gradually beneath it, as shown in Fig. 3. This device D is provided with upright walls D¹, D², upon which the ring rests and between which is formed the channel D² through which the gases can pass. E indicates a gas burner which is projected into the opening B¹ when a ring is located in the furnace and ready for heating. F indicates the ring in position in the furnace.

In operation, the door B is open and a ring F rolled into the furnace on the U beam C until it is supported on the device indicated at D. The door B is then closed and the gas blast introduced through the nozzle E into the bottom of the furnace, the burning gases fill the furnace, passing under the ring supported on the device D and sweeping up the curved back of the furnace as well as through the space between the door and the ring and finally the gases escape through the opening B². By this simple device the rings are easily handled and promptly and effectively heated.

Having now described my invention, what I claim as new and desire to secure by Letters Patent, is:

A narrow upright furnace for heating steel rings having side walls, a curved rear wall and an open front of substantially the height of the furnace, in combination with a door formed to partially close the open front of the furnace and leave openings at the top and bottom thereof and a ring support located at the bottom of the furnace shaped as described to hold the band above the furnace bottom.

RIDGEWAY REGARS.
